Primary Examiner — Kelley Donnelly

(57) **CLAIM**

The ornamental design for an adjustable shelf insert for an open locker, as shown and described.

DESCRIPTION

FIG. 1 is a perspective view of an adjustable shelf insert for an open locker showing my new design;
FIG. 2 is a front view thereof shown in an exploded position, the opposite side being a mirror image;

FIG. 3 is a side view thereof shown in an exploded position, the opposite side being a mirror image; and,

FIG. 4 is a top view thereof shown in an exploded position, the opposite side being a mirror image.

In FIG. 1, the broken lines showing of environmental structure for purposes of illustrating the adjustable shelf insert for an open locker in a condition of use. The broken lines and the structure they depict form no part of the claimed design.

1 Claim, 4 Drawing Sheets

FIG. 1

FIG. 2
